UNITED STATES PATENT OFFICE.

RUSSELL C. STOKES AND EDWARD V. JORDAN, OF DOVER, NEW JERSEY, ASSIGNEES TO
STOKES MANUFACTURING CORPORATION, OF DOVER, NEW JERSEY, A CORPORATION OF DELAWARE.

SAND CUTTING AND MIXING MACHINE.

Application filed June 4, 1921. Serial No. 475,088.

To all whom it may concern:

Be it known that we, RUSSELL C. STOKES and EDWARD V. JORDAN, citizens of the United States, and residents of Dover, in the county of Morris and State of New Jersey, have invented certain new and useful Improvements in Sand Cutting and Mixing Machines, of which the following is a specification.

10 This invention relates to motor propelled cutting and mixing machines for foundry sand arranged in a ridge upon the floor of a foundry by running the machine over the sand ridge and reforming the same in a ridge in the rear of the machine, and it is the primary object of the invention to improve the construction and arrangement of machines of this character to cheapen the cost of construction and at the same time 20 increase the operating efficiency of the machine.

It is a further object of the invention to provide improved driving means for the traction wheels of the machine and the sand 25 mixing and cutting means, said driving means being constructed and arranged whereby the traction wheels may be connected to the driving means to propel the machine and simultaneously therewith operating the sand cutting and mixing means, and whereby the traction wheels and the sand cutting and mixing means may be operated independently of each other.

It is another object of the invention to 35 provide in a machine of this character steering wheels adjustable to different angular positions to change the direction of travel of the machine, and to provide means operative when the steering means are adjusted 40 to one angular position to disconnect one of the traction wheels from the driving means, and as the steering wheels are adjusted in an opposite angular direction to disconnect the other traction wheel from the driving 45 means.

A further object of the invention relates 50 to improved means for automatically disconnecting the sand cutting and mixing means from the driving means when said means encounters an obstruction, such as a casting, in the sand pile or ridge to stop the operation of said means.

It is still another object of the invention to provide an improved friction driving

means in machines of this character including a friction driving disk and a pair of friction wheels to co-operate with said disk to operate the traction wheels and sand cutting and mixing means independently of each other, whereby the traction wheels and sand cutting and mixing means may be operated simultaneously or independently of each other, and to provide means to equalize the frictional engagement of the disk with said friction wheels.

In machines of this character the sand cutting and mixing means consists of a rotatable drum arranged with means to maintain the sand within predetermined limits laterally of the pile or ridge, and having radially extending fingers between said means to cut and mix the sand, said drum being adjustable into and out of operative relation with the sand, and it is a further object of the invention to provide improved means to raise and lower the drum either manually or through the driving means, and to provide an improved mounting for the drum to take up any lateral torsional strains to which the drum may be subjected during the travel of the machine and the rotation of the drum.

Other objects and advantages will herein-after appear.

In the drawings accompanying and forming a part of this specification Figure 1 is a plan view of a sand cutting and mixing machine, partly broken away, with our improved means applied thereto.

Figure 2 is a side elevation looking at the bottom of Figure 1.

Figure 3 is an end elevation of the sand cutting machine looking at the rear thereof.

Figure 4 is a front elevation of the sand cutting and mixing drum.

Figure 5 is a longitudinal sectional view of means to releasably connect the sand cutting and mixing drum with driving means and the means to automatically release the drum when it encounters an obstruction in the travel and rotation thereof.

Figure 6 is an end view looking at the left of Figure 5.

Figure 7 is a plan view of the means to releasably connect the traction wheels to the driving means, and showing the connection of said wheels with the steering wheels whereby to release one of the traction wheels

as the steering wheels are adjusted in one angular direction and to release the other traction wheel as the steering wheels are adjusted in an opposite direction.

5 Figure 8 is a front elevation to show the mounting of the carriage of the machine upon the steering wheels and the connecting of the wheels to simultaneously adjust said wheels to the same angular direction.

10 Figure 9 is a front elevation; and Figure 10 is a side elevation of means mounted upon the drum carrying sand cutting and mixing fingers.

15 Figure 11 is a plan view of one of the connections of the drum to the carriage of the machine.

20 Figure 12 is a rear elevation of the drum showing in a diagrammatic manner the position the drum may assume when encountering and riding over an obstruction to prevent lateral torsional straining of the drum; and

25 Figure 13 is a detail view in plan of the means for raising and lowering the drum in the carriage.

Similar characters of reference designate like parts throughout the different views of the drawings.

In the embodiment of the invention shown 30 in the drawings a carriage for carrying the operative mechanism is provided comprising a frame (designated in a general way by F) supported at the rear by a pair of traction wheels 10, 10' rotatably supported on axles 35 carried at the extremities of diagonal members 11, 11' of the frame. The forward end of the carriage frame is supported by a pair of steering wheels 12, 12' rotatably carried in forks 13, 13' of posts mounted to rotate 40 on vertical axes in a transverse member 14, as shown at 15, the forward end of the carriage frame being supported upon said transverse member 14 by a king bolt 15' in line with the longitudinal axis of the frame, said bolt passing through brackets fixed to the transverse member 14 and a transverse member 16 of the carriage frame as clearly 45 shown in Figure 8. Both of the steering wheels are adapted to be simultaneously adjusted in the same angular direction, as shown in dotted lines in Figure 7, by rotating the wheel carrying forks and to operatively connect the wheel forks to effect this movement they are connected by a cable or 50 chain 17 adjustably connected at opposite ends, as by a turn buckle 18, said cable passing around grooved wheels 19 fixed to the post of each of the wheel forks, and movement is imparted to said wheels by a manually operated handle 20 connected to the 55 extended end of the post of one of the wheel forks.

The carriage is propelled by suitable motive or driving means, such as an electric motor or an internal combustion engine, (in-

dicated in a general way at M) mounted upon the frame. The motor is operatively connected to the traction wheels by friction power transmission mechanism comprising a friction disk 21 fixed to a shaft 22 journaled in bearings 23 mounted upon a base 24 adjustably mounted upon the carriage frame in a manner and for a purpose hereinafter set forth. The disk shaft is connected to the shaft of the driving means or motor by a sprocket chain 25 passing around a sprocket wheel 26 fixed to the shaft of the motor and a sprocket wheel 27 fixed to the disk shaft. A wheel 28 to have frictional engagement with the friction disk is mounted on a shaft 29 to rotate therewith and have sliding movement thereon, said shaft being journaled in bearings upon the frame. The wheel 28 is adjusted on the shaft 29 and radially of the face of the disk by a pivoted lever 30 arranged to engage an annular groove 31 in the hub of the wheel. The shaft 29 is connected to a driving shaft 32 through a standard change speed and reversing gear mechanism (designated in a general way by G), by means of a sprocket chain 23 passing around a sprocket 34 on the driving shaft of the gear mechanism G and a sprocket wheel 35 on the shaft 32. The traction wheels are operatively connected to the driving shaft 32 one independently of the other by a pair of clutches (Figure 7), one member 36, 36' of each of the clutches being loosely mounted upon the shaft and connected to the traction wheels by sprocket chains 37, 37' (Figure 1) passing around sprocket wheels 38, 38' connected to said clutch members and sprocket wheels 39, 39' rotatable with the traction wheels. The other members 40, 40' of the clutches are 100 mounted upon the shaft 32 to rotate therewith and have sliding movement thereon and normally urged by springs 41, 41' to position to operatively engage the clutch members 36, 36' and connect the traction 105 wheels to the driving shaft 32.

To facilitate the turning of corners means are provided to automatically disconnect the traction wheel from the driving shaft 32 which is at the inner side of the machine. For this purpose chains or cables 42, 42' consisting of adjustably connected sections are connected at one end to the posts of the respective steering wheel forks 13, 13', or to drums mounted upon said post, to be wound upon and paid off from said post by the angular adjustment of the steering wheels. The other ends of the cables are connected to one arm of bell crank levers 43, 43' pivotally supported upon the frame, the other arms of 120 the levers being arranged to engage annular grooves in the hubs of the clutch members 40, 40'. It will be obvious that should the steering wheels be adjusted to the dotted line position shown in Figure 7 that the 125

cable 42 will be wound upon the post of the fork 13 moving the lever 43 to the dotted line position and throwing the clutch member 40 out of engagement with the clutch member 36 thereby disconnecting the traction wheel 10 from the driving shaft 32. As the steering wheels are adjusted to direct the machine along a straight course the clutch member 40 is released and again thrown into operative engagement with the clutch member 36 by its spring 41. Should the steering wheels be adjusted to angular position reverse to that shown in dotted lines in Figure 7 the clutch member 40' will be released in a manner similar to the clutch member 40.

To cut and mix the sand during the travel of the carriage a sand cutting and mixing drum is rotatably mounted in the carriage, said drum comprising a pair of heads 44 fixed in spaced relation upon a shaft 45 and connected by circumferentially disposed angle iron bars 46. The drum shaft 45 is rotatably mounted in a pair of angle brackets 47 adjustably secured at one end to arms 48 pivotally supported by brackets 49 fixed to the frame of the carriage, the drum being supported by wheels or rollers 50 rotatably carried by arms 51 adjustably connected to the angle brackets 47. The drum is provided at opposite ends with rigid helical blades 52 extending from the ends of the drum inward. These blades 52 during the rotation of the drum operate to move and maintain the sand in a ridge toward the center of the drum.

To cut and mix the sand a plurality of series of fingers 53 are provided circumferentially disposed around the drum within the blades 52. These fingers are mounted in bars 54 (Figures 9 and 10) pivotally mounted upon the drum bars 46 by bolts 56 (Figure 5) passing through perforations in lugs 55 at opposite ends of the finger bars and lugs 57 fixed to the drum bars 46. The finger bars are normally yieldingly urged in a direction with the rotation of the drum as indicated by the arrow in Figure 3, to position to extend radially from the drum by springs 58 connected at one end to a depending lug 59 and the other ends adjustably connected to the drum bars 46. The finger carrying bars are mounted upon the drum so that the fingers of one bar will be in staggered relation to the fingers of adjacent bars as clearly shown in Figure 4.

The drum is operatively connected to the driving means or motor M to be driven thereby through a friction wheel 60 mounted on a shaft 61 journalled upon the carriage frame co-axially with the shaft 29, said wheel having sliding movement on said shaft and rotatable therewith. The friction wheel is adapted to frictionally engage the

friction disk 21 at the side of its axis of rotation opposite to the disk 28. The friction wheel 60 is adjustable upon its shaft radially of the friction disk to vary the speed of rotation thereof by a pivoted lever 70 70 arranged to engage an angular groove 63 in the hub of the friction wheel. The movement of the shaft 61 is transmitted to a shaft 64 by a sprocket chain 65 passing around a sprocket wheel 66 on shaft 61 and 75 a sprocket wheel 67 on shaft 64, and the movement of the latter shaft is transmitted to the drum by a sprocket chain 68 passing around a sprocket wheel 69 on shaft 64 and a sprocket wheel 70 loose on the drum shaft 80 45. (Figure 5). The sprocket wheel 70 is releasably connected to the drum shaft by clutching mechanism consisting of a head 71 fixed on the drum shaft and a head 72 mounted on the drum shaft to rotate therewith and have sliding movement thereon, said head carrying pins 73 slidably engaging in perforations in the head 71 and in recesses in the hub of the sprocket 70. As stated the drum is adapted to be automatically released from the driving means by the sand cutting and mixing fingers encountering an obstruction, such as a casting, in the sand. For this purpose, means are provided to uncouple the sprocket wheel 90 70 from the drum shaft, comprising a yoke 74 pivotally connected to one end of one of a pair of toggle links 75 pivotally carried by a collar 76 fixed to the drum shaft, the other ends of the links being pivotally connected to a pair of links 77 pivotally connected at the opposite ends to the heads 72, as at 78. The yoke 74 is operatively connected to one of the finger carrying bars 54 by a rod 79 hingedly connected at one end 105 to a finger carrying bar, as at 80 (Figures 2, 6 and 7), the opposite end slidably engaging a socket in a lug 81 of the yoke and the inward movement limited by a collar 82 fixed to the rod. As the finger carrying bar to which the rod 79 is connected encounters an obstruction and is moved in the action of a spring 58, the rod through its connection with the toggle linkage 75, 77 110 will break the toggle moving the same to the dotted line position shown in Figure 5 and in co-operation with springs 83 will move the pin carrying head 72 against the action of an equalizing spring 84 to disconnect the pins 73 from the hub of sprocket 70. As soon as the obstruction is removed the drum may again be coupled to the driving sprocket 70 by manually forcing the toggle members 75, 77 into normal position shown in full lines in Figure 5.

The friction wheel 60 may be adjusted on its shafts to throw said wheel into and out of frictional engagement with the driving disk 21 to drive the traction wheels independent of the drum or vice versa. To 130

equalize the pressure of the disk 21 on the friction wheels, or either one of said wheels, the disk supporting base 24 is adjustably mounted upon the carriage frame. For this purpose the base 24 is arranged with angular or curved slots 85 (Figure 1), and the base is secured to the frame by bolts 86 passing through said slots and engaging a fixed part of the frame. To equalize and take up lateral thrust of the disk the base at one side of the axis of the disk shaft engages an adjustable abutment in the form of a set screw 87, and an adjustable abutment in the form of a set screw 88 at the opposite side of the axis of the disk shaft engages a spring 89 interposed between said abutment and the side of the disk supporting base. This spring 89 operates to exert a greater frictional stress against the wheel 60 when both of the friction wheels are in engagement with the disk.

To raise and lower the drum a pair of cables 90 are secured at one end to the drum, said cables passing over pulleys 91 carried by standards 92 of the frame with the opposite ends connected to drums 93 fixed to a shaft 94 journalled upon the frame work. By rotating the shaft 94 in one direction it will be obvious that the cables will be wound upon the drums thereby raising the sand mixing drum and when the shaft is rotated in an opposite direction the cables are paid off from the drums 93 and the mixing drum is lowered with the drum supporting wheels 50 to engage the ground or floor. To lower and raise the mixing drum a worm wheel 95 is fixed upon the shaft 94 with which a worm 96 meshes said worm being carried by a shaft 97 rotatably mounted upon the frame and extending to the front of the machine and at which end it has a crank handle 98 fixed thereto whereby the shaft may be normally rotated. The meshing of the worm 96 with the worm wheel 95 maintains the mixing drum in adjusted position. The mixing drum may also be raised or lowered by the driving means. For this purpose a pair of opposite friction cone faces 99—99 (Figure 13) are adapted to be thrown into frictional engagement with a similarly formed friction cone face 100 by imparting longitudinal movement to the shaft 97, said shaft being mounted in a thrust box to permit of such longitudinal movement. The driving face 100 is fixed to a shaft 101 journalled upon the frame and is driven from the shaft 29 by a sprocket chain 102 passing around a sprocket wheel 103 on shaft 29 and a sprocket wheel 104 fixed to the shaft 101. To take up any torsional strain which may be imparted to the sand mixing drum during the rotating thereof and as it is moved over the sand pile during the propelling of the machine, as by the drum supporting wheels 50 riding over an obstruction, the

drum supporting arms 48 are constructed of a pair of pivotally connected sections, the one section being bent laterally, as at 105 (Figure 11) and the other section of the arms 48' being of U-shape and whereby the arm is pivotally connected to the supporting bracket 49, the two sections being connected by a rivet 106 passing through the connecting portion of the section 48' and the portion 105 whereby the arm sections may have 70 rotative movement relative to each other. Should the drum ride over an obstruction as shown in a diagrammatic manner in Figure 12 the arm sections will be adjusted substantially to the portion as indicated in said 75 Figure 12.

To keep the sand down and prevent the same from being thrown upward by the rotation of the mixing drum a guard 110 is provided and consisting of a sheet of material bent to circular shape as shown in Figure 2. This guard or shield is supported by radius rods 111 connected to the drum support 47 and the opposite ends connected to and supporting the shield adjacent opposite corners, the opposite corners of the shield being connected to the arms 48, as shown at 85 112. By this arrangement the guard is mounted to be raised and lowered with the drum.

Having thus described our invention we claim:

1. In a sand cutting and mixing machine; a carriage supported by traction and steering wheels; a drum rotatably supported by the carriage; a series of bars pivotally carried by the drum on axes parallel with the drum and circumferentially disposed around the drum in spaced relation, each of said bars carrying a series of fingers and the bars arranged with the fingers of one bar in staggered relation to the fingers of adjacent bars; means to yieldingly maintain the bars in position with the fingers to extend radially from the drum; driving means for the drum; a clutch to releasably couple the drum to the driving means, one of said clutch members having movement independently of the drum and operatively connected to the driving means, and the other clutch member rotatable with and having sliding movement axially of the drum; a spring to normally urge said latter clutch member out of operative connection with the other clutch member; means to normally maintain the sliding clutch member in operative engagement with the other clutch member against the action of the spring; and means operative by a finger carrying bar to uncouple the clutch when the fingers of said bar encounters an obstruction in the rotation of the drum; comprising a toggle link connection, one link of the toggle having a connection with the sliding clutch member and the other pivotally 120 connected to the driving means.

- mounted upon the axle of the drum, and an actuator connected to said latter link and operative by a finger carrying bar as it encounters an obstruction to break the toggle for the purpose specified.
2. In a sand cutting and mixing machine, a carriage including a pair of traction wheels; a sand cutting and mixing drum rotatably mounted in the carriage; driving means for the traction wheels and drum including a friction disk; a friction wheel to co-operate with said disk operatively connected to the traction wheels; a second friction wheel to co-operate with the disk and operatively connected to the drum; and an adjustable support for said friction disk, comprising a bearing supporting base arranged with slots, securing means to engage in said slots and secured in a fixed part of the carriage to mount the bearing base thereon, a pair of set screws adjustably mounted on the carriage at opposite sides of the bearing base, one of said screws being adapted to engage the base and the other a spring interposed between the base and set screw for the purpose specified.
3. In a sand cutting and mixing machine, a carriage; a sand cutting and mixing drum; a pair of arms pivotally supported by the carriage and rotatably carrying the drum; driving means for the drum; and means to raise and lower said drum, comprising a rotatable shaft having a worm wheel thereon and a pair of drums mounted thereon, a pair of cables one end of the cables being connected to each of the drum carrying arms, and the other ends connected to the shaft drums to be wound upon and paid off from said drums by the rotation of the shaft, a shaft having a worm to mesh with the worm wheel, a friction wheel operatively connected to the driving means, and a pair of friction wheels on the worm shaft either one of which is adapted to be brought into operative engagement with the friction driving wheel for the purpose specified.
4. In a sand cutting and mixing machine, a carriage, a sand cutting and mixing drum, and a pair of arms pivotally supported by the carriage and rotatably carrying said drum, said arms being adjustable and arranged to take up lateral torsional strains to which the drum may be subjected.
5. In a sand cutting and mixing machine, a carriage, a sand cutting and mixing drum, and a pair of arms pivotally supported by the carriage and rotatably carrying said drum, said arms being adjustable and arranged to take up lateral torsional strains to which the drum may be subjected.
6. In a sand cutting and mixing machine, a carriage, a sand cutting and mixing drum, and a pair of arms pivotally supported by the carriage and rotatably carrying said drum each of said arms comprising sections to have adjustment on an axis transverse to the axis of rotation of the drum for the purpose specified.
7. In a sand cutting and mixing machine, a traction carriage, a sand mixing and cutting drum, means to releasably support said drum and mount the same in the carriage to be raised and lowered, and a guard to extend around the upper portion of the drum and adapted to participate in the raising and lowering movements of the drum.

Signed at Dover, in the county of Morris and State of New Jersey, this 21st day of May, 1921.

RUSSELL C. STOKES.
EDWARD V. JORDAN.
